Des. 242,525
Patented Nov. 30, 1976

242,525

PLASTIC SLEEVE-ENCASED BOTTLE

Raymond G. Reynolds, Sylvania, Ohio, assignor to
Owens-Illinois, Inc., Toledo, Ohio

Filed May 7, 1975, Ser. No. 575,307

Term of patent 14 years

Int. Cl. D9—01

U.S. Cl. D9—12

FIG. 1

FIG. 2

FIG. 3

FIG. 4

FIG. 1 is a front elevational view of a plastic sleeve-encased bottle showing my new design;

FIG. 2 is a top plan view thereof;

FIG. 3 is a rear elevational view thereof; and

FIG. 4 is a sectional view taken on line 4 of FIG. 3.

I claim:

The ornamental design for a plastic sleeve-encased bottle, substantially as shown.
